UNITED STATES PATENT OFFICE.

JOHANNE JOHANSEN, OF NEWPORT, RHODE ISLAND.

FURNITURE POLISH.

No Drawing.

Application filed August 2, 1924. Serial No. 729,719.

To all whom it may concern:

Be it known that I, JOHANNE JOHANSEN, a citizen of the United States of America, and resident of Newport, in the county of 5 Newport and State of Rhode Island, have invented certain new and useful Improvements in Furniture Polish, of which the following is a specification.

This invention relates to furniture polish 10 and has for its object the production of a furniture polish which is free of acids or any injurious property and furthermore, an object of the invention is to produce a furniture polish which will retain its 15 properties, without deterioration, for a long period of time, the said polish being unaffected by changes in temperature or atmospheric conditions within predetermined bounds, as for instance the conditions existing 20 in the Temperate Zones of the world.

A further object of this invention is to produce a furniture polish which is comparatively inexpensive while at the same time it serves to remove the appearance of 25 scratches or other marred condition of the finish of the furniture without leaving a deposit which will rub off or be freed by dampness or the like.

With the foregoing and other objects in 30 view, the invention consists in a furniture polish comprising the following ingredients in substantially the proportions to be hereinafter more fully set forth and claimed.

In carrying out my invention in practice, linseed oil, kerosene, vinegar, turpentine and 35 spirits of camphor are employed, and preferably the said ingredients are used in substantially the proportions as follows, viz: linseed oil, 6 oz.; kerosene, 4 oz.; vinegar, 4 oz.; turpentine, 2 oz.; spirits of camphor, 40 1 teaspoonful.

Preferably in the compounding of the ingredients, the linseed oil, kerosene, vinegar, turpentine and spirits of camphor are thoroughly commingled by agitation, and in 45 applying the furniture polish to the objects to be treated, it is desirable to lightly coat the surface with the polish and thereafter to rub the same until the moisture is absorbed and the surface is perfectly dry. 50

It has been found in practice that if the linseed oil is placed in a glass container and then adding the kerosene, turpentine, vinegar and camphor in the order named and thoroughly shaken, the best results are attained. It has also been desirable to use 55 glass as the best container for the polish.

I claim—

The herein described furniture polish consisting of 6 ounces linseed oil, four ounces 60 kerosene, four ounces vinegar, two ounces turpentine and one teaspoonful spirits of camphor, thoroughly commingled by agitation.

JOHANNE JOHANSEN.
